(57) **CLAIM**

The ornamental design for a trailer, as shown and described.

DESCRIPTION

FIG. 1 is an upper-rear perspective view of a trailer showing
the new design;

FIG. 2 is a lower-front perspective view of the trailer of FIG.
1;

FIG. 3 is a front elevation view of the trailer of FIG. 1;
FIG. 4 is a rear elevation view of the trailer of FIG. 1;

FIG. 5 is a left side elevation view of the trailer of FIG. 1;

FIG. 6 is a right side elevation view of the trailer of FIG. 1;

FIG. 7 is a top plan view of the trailer of FIG. 1; and,

FIG. 8 is a bottom plan view of the trailer of FIG. 1.

The broken lines shown in the drawings illustrate portions of
the trailer that form no part of the claimed design.

1 Claim, 8 Drawing Sheets
